UNITED STATES PATENT OFFICE.

JOHN R. M. CHALFANT AND BESSE PHILLIPS CHALFANT, OF MORGANTOWN, WEST VIRGINIA.

WASHBOILER.

Application filed December 30, 1921. Serial No. 526,021.

To all whom it may concern:

Be it known that we, JOHN R. M. CHALFANT and BESSE PHILLIPS CHALFANT, citizens of the United States of America, and 5 residents of Morgantown, county of Monongalia, and State of West Virginia, have invented certain new and useful Improvements in Washboilers, of which the following is a specification.

10 This invention relates to wash boilers, and it has for its primary object to provide a boiler having a construction which permits of its being divided centrally into two separate compartments with the end in view to provide for the separate boiling at one and the same time of clothes of two different kinds, as fine clothes and coarse clothes, which would otherwise require either that two separate boilers be employed 15 or that two separate boilings be resorted to.

A further object is to provide a wash boiler of the character mentioned which may be employed interchangeably as a single-chamber receptacle, as ordinarily, or as 20 a two-chamber receptacle, the latter being produced by seating therein a removable division wall having the form of a readily 25 slideable panel.

30 A still further object is to provide a vessel of the character mentioned which is equipped with means whereby either or both chambers thereof may be drained of water prior to removal of the clothes, thus greatly 35 reducing the weight and facilitating the removal of the vessel from the fire, in that the vessel with the clothes therein may then be readily lifted and carried to a point where all the clothes can be dumped bodily 40 therefrom.

With these and other objects in view, the invention resides in the features of construction, arrangement of parts and combinations of elements which will hereinafter 45 be exemplified, reference being had to the accompanying drawings, in which—

Figure 1 is a top plan view of the invention; and

50 Figure 2 is a transverse section on line 2—2, Fig. 1.

Referring to said drawings, 1 indicates a wash boiler body having the general elongated oval form common to boilers of this type, the same having a bottom 2. Attached rigidly to the inner sides of the op-

posite side walls of the body 1 and to the bottom 2 substantially midway between the ends thereof is a seating member 3 designed for the reception of a panel-like division wall or slide member 4 by which the interior of 60 the vessel may be divided into two noncommunicating compartments.

Said seating member 3 is preferably formed of a single strip of sheet metal which is bent to form opposite lateral 65 flanges or foot portions 5, leg portions 6 rising from and disposed at right angles to said foot portions, and an intermediate reflex or retrorsal loop 7, said leg portions being united to said loop by opposite inturned 70 lips 8 which are separated by a narrow throat.

The seating member is shaped to conform substantially to the internal transverse shape of the vessel body 1 and has the foot 75 portions 5 thereof suitably attached to the bottom and side walls of said body, as by soldering.

The loop 7 is preferably lined interiorly with a suitable yieldable packing 9, as a 80 rubberized fabric material, adapted to form a close joint with the lower and lateral edges of the division panel 4 when the latter occupies a seated position. Said panel preferably has its opposite lateral edges beaded, as shown at 10, to substantially correspond 85 with the internal formation of the loop, the vertical portions of the latter constituting guideways through which said beaded edges are slideable as the panel is inserted and removed. The panel is very slightly tapered 90 from its upper end downward, and the vertical portions of the loop, or the guideways, are correspondingly inclined inward so that the former becomes more or less closely 95 wedged as it assumes a seated position.

To prevent overheating which would result in melting the solder by which the seating member 3 is attached, one or more perforations 11 may be provided in only one of the leg portions 6 at a suitable point or points, thus affording access for water to the open space 12 between said leg portions. A hand opening 13 is provided in the upper end of the panel, as shown.

As is manifest, when the removable panel 4 occupies seated position the vessel is divided into two compartments in which two kinds of clothing which would otherwise require separate boilings may be separately 110

boiled simultaneously. The water from said compartments may be drawn off through suitably located faucets 14, after which the vessel containing the boiled clothes may 5 be readily carried and the clothes bodily dumped therefrom, thus obviating the usual objectionable practice of transferring dripping clothes on a stick from the wash boiler to another vessel located at a distance from 10 such boiler.

Other advantages of the structure described are readily apparent and therefore need not here be described.

What is claimed is:—

- 15 1. A wash boiler comprising a boiler body, a panel adapted to form a division wall whereby the interior of said body is divided into two compartments, and a seat for said panel permanently mounted on the bottom 20 and sides of said body midway between the ends of the latter, said seat being formed of sheet metal and being bent to form opposite foot and leg portions and an intermediate retrorsal loop, the latter affording a guide channel in which the lateral edges of said panel are receivable.
2. A wash boiler comprising a boiler body, a panel adapted to form a division wall whereby the interior of said body is divided 30 into two compartments, and a seat for said panel permanently mounted on the bottom and sides of said body midway between the ends of the latter, said seat being formed of sheet metal and being bent to form opposite foot and leg portions and an intermediate retrorsal loop, said foot portions being attached to said body and said loop affording a channel in which edges of said panel removably seat to form a water-tight 40 joint.
3. A wash boiler comprising a boiler body, a panel adapted to form a division wall whereby the interior of said body is divided into two compartments, and a seat for said 45 panel permanently mounted on the bottom and sides of said body midway between the ends of the latter, said seat being formed of sheet metal and being bent to form op-

50 posits foot and leg portions and an intermediate retrorsal loop, said foot portions being attached to said body and said loop affording a channel in which edges of said panel are receivable for movement to and from seated position, and a packing lining the interior of said loop.

55 4. A wash boiler comprising a boiler body, a seating member located substantially midway between the ends of said body, said member consisting of a single strip of sheet metal bent to form opposite foot portions, leg portions rising from said foot portions, and a retrorsal loop intermediate said leg portions, said loop opening inward through a throat of restricted width, and a panel 60 slideable into and out of seated relation to said seating member whereby said body is divided into two compartments, the bottom and lateral edges of said panel being receivable within said loop and forming a tight joint with the latter, one of said leg 70 portions being provided with perforations.

5. A wash boiler comprising a boiler body, a seating member located substantially midway between the ends of said body, said member consisting of a single strip of sheet 75 metal bent to form opposite foot portions, leg portions rising from said foot portions, and a retrorsal loop intermediate said leg portions, said loop opening inward through a throat of restricted width, and a panel 80 slideable into and out of seated relation to said seating member whereby said body is divided into two compartments, the bottom and lateral edges of said panel being receivable within said loop and forming a tight joint with the latter, and faucets 85 carried by said body and affording means for draining said separated compartments.

In testimony whereof we affix our signatures in presence of two witnesses.

JOHN R. M. CHALFANT.
BESSE PHILLIPS CHALFANT.
